(57) **CLAIM**

The ornamental design for a camera, as shown and described.

DESCRIPTION

FIG. 1 is a perspective view of a camera showing my new design.

FIG. 2 is a top plan view of the camera shown in FIG. 1 showing my new design.

FIG. 3 is a left side elevation view of the camera shown in FIG. 1 showing my new design.

FIG. 4 is a front elevation view of the camera shown in FIG. 1 showing my new design.

FIG. 5 is a bottom plan view of the camera shown in FIG. 1 showing my new design.

FIG. 6 is a rear elevation view of the camera shown in FIG. 1 showing my new design; and,

FIG. 7 is a right side elevation view of the camera shown in FIG. 1 showing my new design.

The broken lines illustrate portions of the camera that form no part of the claimed design.
